FREDERICK W. WAKEFIELD, OF VERMILION, OHIO. ASSIGNOR TO THE F. W. WAKEFIELD
BRASS COMPANY, OF VERMILION, OHIO, A CORPORATION OF OHIO.

SIGNAL-LAMP.

1,231,677.

Specification of Letters Patent. Patented July 3, 1917.

Application filed June 8, 1916. Serial No. 101,445.

To all whom it may concern:

Be it known that I, FREDERICK W. WAKEFIELD, a citizen of the United States, and a resident of Vermilion, county of Erie, and State of Ohio, have invented a new and useful Improvement in Signal-Lamps, of which the following is a specification, the principle of the invention being herein explained and the best mode in which I have contemplated applying that principle, so as to distinguish it from other inventions.

The object of the present invention is a signal lamp particularly fitted for use on automobiles and motor boats where it is desirable to have a single lamp which will project a beam of light of different colors. In the present lamp I have designed an inexpensive lamp which is adapted to project light of several colors, and I have also provided means for changing the colors so that the lamp may be a rather small searchlight with provision for quickly shifting where a colored beam is desirable, as for use in signaling or as the side light on a motor boat. To the accomplishment of the foregoing and related ends, said invention, then, consists of the means hereinafter fully described and particularly pointed out in the claims.

30 The annexed drawing and the following description set forth in detail certain mechanism embodying the invention, such disclosed means constituting, however, but one of various mechanical forms in which the principle of the invention may be used.

In said annexed drawing:

Figure 1 is a longitudinal section through the lamp; and Fig. 2 is a section taken on the line 2—2, Fig. 1.

40 The present lamp consists of the usual outer casing or shell 1 of any desired form, except that it is open at both ends, said casing having its front end closed by a glass lens 2 mounted therein in the usual way and having its rear end closed by a separable plate 4 that is normally held in place by screws 15, or other suitable means. A reflector 3 is held in the casing, said reflector being of general annular form, having a central aperture 5 therein, through which the lamp bulb 8, or other lighting element, supported as hereinafter described, projects from the rear, so as to occupy a proper position with respect to said reflector.

55 The plate 4 not only thus supports this

lamp bulb, but also carries the other parts of the lamp which are features of present interest, all these parts being removable with the plate, so that if it is necessary to replace or repair any such portion, this may be readily accomplished.

One of the parts thus carried by said plate 4 is the reflector center 16, which is of the same curvature as the main reflector 3, but is a trifle smaller in diameter than the aperture 5 therein, so as to leave an annular space for the purpose presently to be described. This reflector center is attached to the plate 4 by means of strips, or fingers 6, and serves in turn to support a lamp-socket 7 of any desired type in which the bulb 8 is mounted. A switch 9, rotatably mounted in the plate 4, is interposed in one of the leads 17, that form the lamp circuit, so as to serve to turn the lamp 8 on or off, as desired.

From the foregoing, it will be seen that both the lamp and the switch controlling the same are carried by the detachable plate 4, so as to be removable therewith from the casing 1, such removal being further facilitated by having the leads 17 pass through an opening 19 in the plate instead of in the casing.

50 In addition to the switch 9, worm screws 10, two in number as shown are rotatably mounted in this same plate 4, and these are provided with knurled heads 11 or other equally convenient means for operating the same. As here shown, two transparent colored sleeves 12 and 13 are concentrically mounted around the socket 7 so as to be capable of longitudinal movement axially of said socket, each such sleeve having a threaded nut attached thereto and adapted to receive one of the worm screws 10. As illustrated in Fig. 1, one of these sleeves 12 is in its extended position, in which it projects through the annular space between the two reflector-portions 3 and 16 and laterally surrounds the bulb 8, and in this position all the light rays must obviously pass through the sleeve before striking the main reflector portion 3. Such rays, however, as strike the central portion 16 of the reflector will be directed, in the main, as a clear beam of light, so that the result will be a broad annular beam of colored light surrounding a central beam or core of white light. It will be understood that a single sleeve will be

often used of a single color (as red), and where two are employed, one will be red and one green, or they may be other colors depending on the use to which the lamp is to be put.

The worm screws 10 are preferably formed with a very steep pitch so that only a few turns are required to move a sleeve from its extended to its retracted position. The two 10 knurled beads of the screws and the switch button will be so arranged as to be readily grasped and distinguished from each other. The sleeves will be formed of any suitable transparent material such as glass, celluloid 15 or mica, and as they are removably mounted with the rear plate they can be replaced or changed very easily.

Such a lamp is particularly suitable for use as a side light on a motor boat where 20 a colored light is needed, as it can be taken off and used for ordinary lighting purposes. For use on automobiles, as a searchlight and as a danger signal when one of the colored sleeves is used, the present device presents 25 a number of advantages. At the same time it is inexpensive to manufacture and in case the lamp bulb requires to be changed after the lamp is installed, by simply removing the plate, not only is such bulb rendered 30 directly accessible, but the wiring connections and other operative parts as well. By reason of the fact that a portion of the reflected light, even when the colored transparent sleeve is in operative position, re- 35 mains unaffected by such sleeve, the driver of the vehicle still retains in a sufficient measure to be of use in selecting his road, or for other purposes, the illuminative effect of the central uncolored portion of the re- 40 flected beam.

I therefore particularly point out and distinctly claim as my invention:—

1. In a lamp of the character described, the combination of a reflector comprising a 45 main annular portion and a central portion, an annular space being left between such portions; a lighting element supported from said central reflector portion; and a slidably mounted sleeve normally positioned to the rear of said reflector but movable through such annular space to laterally surround said lighting element, substantially as described.

2. In a lamp of the character described, 55 the combination of a reflector comprising a main annular portion and a central portion, an annular space being left between such portions; a lighting element supported from said central reflector portion; and a slidably mounted sleeve of transparent colored material normally positioned to the rear of said reflector but movable through such annular space to laterally surround said lighting element, substantially as described.

3. In a lamp of the character described, the combination of a reflector comprising a main annular portion and a central portion, an annular space being left between such portions; a lighting element supported 70 from said central reflector portion; and a plurality of concentric, slidably mounted transparent sleeves of different colors normally positioned to the rear of said reflector, but independently movable through such annular space to laterally surround said lighting element, substantially as described.

4. In a lamp of the character described, the combination of a suitable casing open 80 at both ends; a glass closing the front end of said casing; a removable plate closing the rear end of said casing; a reflector mounted in said casing, said reflector comprising a main annular portion, and a central portion carried by said plate, an annular space being left between such portions; a lighting element supported centrally from such central reflector portion; and a sleeve attached to said plate so as to be slidable 85 axially of said lighting element, said sleeve being normally positioned to the rear of said reflector but being movable through the annular space therein to laterally surround said lighting element.

5. In a lamp of the character described, the combination of a suitable casing open 90 at both ends; a glass closing the front end of said casing; a removable plate closing the rear end of said casing; a reflector mounted in said casing, said reflector comprising a main annular portion, and a central portion carried by said plate, an annular space being left between such portions; a lighting element supported 95 centrally from such central reflector portion; and a sleeve of transparent colored material attached to said plate so as to be slid- 10 axially of said lighting element, said sleeve being normally positioned to the rear of said reflector but being movable through the annular space therein to laterally surround said lighting element.

6. In a lamp of the character described, the combination of a suitable casing open 11 at both ends; a glass closing the front end of said casing; a removable plate closing the rear end of said casing; a reflector mounted in said casing, said reflector comprising a main annular portion, and a central portion carried by said plate, an annular space being left between such portions; a lighting element supported centrally from such central reflector portion; a sleeve attached to said plate so as to be slidable axi- 12 ally of said lighting element, said sleeve being normally positioned to the rear of said reflector but being movable through the annular space therein to laterally surround said lighting element; and means for 13

operating said sleeve also carried by said plate.

7. In a lamp of the character described, the combination of a suitable casing open at both ends; a glass closing the front end of said casing; a removable plate closing the rear end of said casing; a reflector mounted in said casing, said reflector comprising a main annular portion, and a central portion carried by said plate, an annular space being left between such portions; a lighting element supported centrally from such central reflector portion; a sleeve attached to said plate so as to be slidable axially of said lighting element, said sleeve being normally positioned to the rear of said reflector but being movable through the annular space therein to laterally surround said lighting element; and means for operating said sleeve also carried by said plate, said means comprising a screw rotatably mounted in said plate and having threaded engagement with said sleeve.

8. In a lamp of the character described, the combination of a suitable casing open at both ends; a glass closing the front end of said casing; a removable plate closing the rear end of said casing; a reflector mounted in said casing, said reflector having a central aperture; an electric lamp-socket carried by said plate and projecting through such aperture to support a lamp in proper position with respect to said reflector; and a switch for controlling such lamp also carried by said plate.

9. In a lamp of the character described, the combination of a suitable casing open at both ends; a glass closing the front end of said casing; a removable plate closing the rear end of said casing; a reflector mounted in said casing, said reflector comprising a main annular portion and a central portion, the latter being attached to said plate so as to be removable therewith; an electric lamp-socket attached to said central reflector-portion and adapted to support a lamp in proper position with respect to said reflector; and a switch for controlling such lamp also carried by said plate.

10. In a lamp of the character described, the combination of a suitable casing open at both ends; a glass closing the front end of said casing; a removable plate closing the rear end of said casing; a reflector mounted in said casing, said reflector comprising a main annular portion and a central portion, the latter being attached to said plate so as to be removable therewith, an annular space being left between said reflector-portions; an electric lamp-socket attached to said central reflector-portion and adapted to support a lamp in proper position with respect to said reflector; a switch for controlling such lamp carried by said plate; and a sleeve also attached to said plate so as to be slidable axially of said lamp-socket, said sleeve being normally positioned to the rear of said reflector but being movable through the annular space therein to laterally surround a lamp in said socket.

70

11. In a lamp of the character described, the combination of a suitable casing open at both ends; a glass closing the front end of said casing; a removable plate closing the rear end of said casing; a reflector mounted in said casing, said reflector comprising a main annular portion and a central portion, the latter being attached to said plate so as to be removable therewith, an annular space being left between said reflector-portions; an electric lamp-socket attached to said central reflector-portion and adapted to support a lamp in proper position with respect to said reflector; a switch for controlling such lamp carried by said plate; a sleeve also attached to said plate so as to be slidable axially of said lamp-socket, said sleeve being normally positioned to the rear of said reflector but being removable through the annular space therein to laterally surround a lamp in said socket; and means for operating said sleeve carried by said plate.
